ARVID H. NERO, OF NEW BRITAIN, CONNECTICUT, ASSIGNOR TO THE ARROW ELECTRIC COMPANY, OF HARTFORD, CONNECTICUT, A CORPORATION OF CONNECTICUT.

ELECTRICAL CONTACT.

1,257,917.

Specification of Letters Patent. Patented Feb. 26, 1918.

Application filed July 24, 1917. Serial No. 182,422.

To all whom it may concern:

Be it known that I, ARVID H. NERO, a citizen of the United States of America, and residing at New Britain, in the county of 5 Hartford and State of Connecticut, have invented a certain new and useful Improvement in Electrical Contacts, of which the following is a specification.

My invention relates to electrical contacts, 10 and particularly to contacts for attachment plug receptacles, the object of my invention being to provide a contact brush formed from spring sheet metal and of such construction that it is adapted to withstand repeated engagement with the jacks of an attachment plug without danger of excessive deformation.

In the accompanying drawing.

Figure 1 is a vertical section through an 20 attachment plug receptacle having therewith a coöperating plug shown in side elevation;

Fig. 2 is a perspective of one of the receptacle contacts.

It has been common practice heretofore 25 to make a receptacle contact of the general form shown from a strap of spring sheet metal, one end of which is bent back upon itself to form a spring terminal or brush 30 for engagement by a jack of a coöperating plug. It has been found, however, that repeated insertion of the jack into engagement with the brush contact, especially careless insertion or a withdrawal at an angle 35 to the normal direction of motion, tends to flatten the brush against the body of the strap and thus deprive the contact of the resiliency which is desired for its most efficient operation. To overcome this difficulty 40 it is proposed to reinforce the contact brush by an auxiliary spring such as that shown in my recent Patent No. 1,231,417.

I have now discovered that the contact brush can be efficiently protected against 45 deformation by the simple expedient illustrated in the accompanying drawing. The construction here illustrated is for the most part of common type in separable attachment plugs, and comprises an insulating button 10, pierced at 11 and 12 to form on the one hand, guide-ways for the jacks 13 and 14 of the coöperating cap or plug element 15, and on the other hand chambers 50 for the receiving contacts to which the in-

vention particularly relates. These contacts comprise straps 16 and 17 extending into the piercings 11 and 12 from the entering end of the button 10 and bent back upon themselves at their outer ends to form contact brushes 18 and 19 with which the jacks 55 13 and 14 on the plug cap engage on the insertion thereof. The terminal strap 16 is carried by and riveted to the screw shell contact 20 on the button 10 while the strap 17 is carried down below the central boss 21 60 of the button and forms the center contact 22 thereof, being secured into position by a rivet 23, one end of which is embedded in the molded insulation out of which the button 10 is formed.

At its outer end each strap 16 and 17 is connected to its brush contact 18 and 19 respectively, by a return bend 24 which insures the spring action of each contact brush and causes a strong wiping action against 75 the jacks 13 and 14. Such a wiping action is very desirable to insure good electrical contact between these parts. Repeated insertion of the jacks however, or the careless manipulation of the plug cap 15, may result 80 in the "ironing down" of the brushes 18 and 19 against the straps 16 and 17 to such an extent that the bends 24 are practically eliminated and the spring action of the brushes lost. I have found that this action 85 can be absolutely prevented by forming in each strap a bump 25 adjacent the bend 24 and projecting into the space between the adjacent faces of the strap and the brush. This bump maintains that portion of the 90 brush adjacent the bend in substantially normal position even under pressure from the jacks which would normally deform the brush. It is impossible to "iron down" the bend 24 since in case of deforming pressure 95 upon the free end of the brush by the jack, the brush bears against bump 25 and bends at this point as on a pivot so that the deformation, if it is occasioned at all, is confined to the free end of the brush and does 100 not destroy the resiliency of the contact by flattening out the bend 24.

The safe-guard described is one which can be readily incorporated in the contact brush at the time of its manufacture without additional expense other than the proper formation of the die which must in any event be utilized to form the brush. Of

course the contact can be applied to flush receptacles or other devices using this type of terminal.

I claim as my invention:

- 5 A contact for electrical devices comprising a strap of spring metal bent back upon itself at one end to form a contact brush together with a spacing bump formed in said strap adjacent the return bend thereof, and

extending into the space between the adjacent faces of the strap adjacent the bend to prevent excessive deformation of the contact at said return bend by pressure on the brush.

In testimony whereof I have signed my name to this specification.

ARVID H. NERO.
